UNITED STATES PATENT OFFICE.

PIETRO CERONE, OF SYRACUSE, NEW YORK.

DESIGN FOR A PANEL FOR WOOD FURNITURE.

50,566.

Specification for Design.

Patented Apr. 10, 1917.

Application filed August 9, 1916. Serial No. 114,057. Term of patent 3½ years.

To all whom it may concern:

Be it known that I, PIETRO CERONE, a subject of the King of Italy, residing at 654 Burnet avenue, Syracuse, New York, have invented a new, original, and ornamental Design for Panels for Wood Furniture, of which the following is a description, reference being had to the accompanying drawing, forming a part thereof.

The figure is a face view of a portion of one end of a panel for wood furniture show-

ing my new design, the same ornamental configuration continuing indefinitely in any length or width which would be impossible to show as a complete panel.

What I claim is:

The ornamental design for a panel for wood furniture as shown.

PIETRO CERONE.
